UNITED STATES PATENT OFFICE

WEBSTER I. CARPENTER, OF NORFOLK, VIRGINIA

FLUID WARMER

Application filed July 25, 1930. Serial No. 470,748.

This invention relates to a fluid warmer primarily adapted for use in connection with a dental syringe, and has for its primary object to provide, in a manner as hereinafter set forth, a device of such character by means of which water or air of the exact temperature required may be discharged into the syringe in order that a cavity in a sensitive tooth may be irrigated or dried with the proper fluid at body temperature.

10 A further object of the invention is to provide a fluid warmer of the character aforesaid by means of which a supply of fluid may be heated and stored at a required temperature until the same is drawn off for use, thereby insuring a constant and adequate supply of the fluid at the required temperature, irrespective of the rate at which it is desired to draw the fluid from the warmer.

20 A further object of the invention is to provide a fluid warmer of the character aforesaid which includes a replaceable heating unit which may be readily assembled or disassembled with respect to the warmer while 25 the latter is in use in order that the warmer may continue to discharge fluid at the temperature required in the event that the heating unit should become damaged.

With the foregoing and other objects in 30 view, the invention consists of the novel construction, combination and arrangement of parts as hereinafter more particularly described, and as illustrated in the accompanying drawing wherein is shown an embodiment 35 of the invention, but it is to be understood that the description and drawing are to be taken as illustrative and that the invention is intended to be limited only by the scope of the claims hereunto appended.

40 In the accompanying drawing in which like numerals are employed to designate like parts throughout the several views:—

Figure 1 is a vertical section through a fluid warmer in accordance with this invention 45 showing the same in association with a fluid conduit.

Figure 2 is a perspective view of the heating unit forming a part of the warmer.

Figure 3 is a horizontal section through 50 the warmer.

Referring to the drawing in detail, the numeral 1 indicates a casing which is preferably of cylindrical construction having a flanged bottom 2 threaded on the lower end thereof and further having a flanged top 3 threaded on the upper end thereof. The bottom 2 is formed centrally thereof with a threaded opening which is engaged by external threads on the reduced neck 4 of a cup 5 disposed within the casing 1. The neck 4 is of hollow construction and is provided with threads for engagement by the threaded upper end of a hollow outlet plug 6, the lower end of which may be connected in any suitable manner with a fluid conduit, such as 7.

55 The cup 5 is internally threaded for engagement with external threads on the lower end of a cylindrical jacket 8 which extends longitudinally of the casing 1 and has its open upper end arranged in spaced relation to the top 3. Extending into the jacket 8 is a heating element indicated generally at 9 which includes a resistance coil 10 imbedded within a di-electric heat conducting body 11 which is hermetically sealed within a tubular container 12. Secured within the lower end of the container 12 and projecting therebelow into spaced relation to the outlet plug 6 is a heat conducting block 13.

60 Threaded into the upper end of the container 12 is a tube 14, the upper end of which is threaded into a hollow cap 15 having a skirt portion 16 encircling a portion of the tube 14 in concentric, spaced relation thereto. The cap 15 is threaded into an opening 65 formed centrally of the top 3 of the casing and is formed with a flange 17 resting on the upper face of the top 3. The upper end of the tube 14 is closed by means of a plug 18 which is threaded into the cap 15 above the 70 tube 14, and is provided with an opening 19 of proper size to permit the snug passage therethrough of a pair of conductors 20 which extend through the tube 14 and which are connected respectively to the respective 75 ends of the coil 10. The conductors 20 are adapted for connection with a suitable source of electrical energy, not shown.

80 The casing 1 is provided in spaced relation to the bottom thereof with a hollow inlet 100

plug 21 for connection with a fluid supply conduit 22 which is adapted for connection with a suitable source of fluid supply, not shown. Preferably a suitable thermostat, not shown, will be provided within the casing 1 for the purpose of controlling the supply of electrical energy to the resistance coil 10. The inlet plug 21 is in alignment with the resistance coil 10 radially of the casing.

In the operation of the warmer, a fluid is injected thereinto through the inlet plug 21 directly opposite the source of heat within the jacket 8. The fluid thus injected into the casing is slightly warmed by conduction through the wall of the jacket and rises within the casing and flows over the top of the jacket 8 into the interior of the latter to surround the heating element 9 disposed within the jacket. The fluid is heated to a higher degree immediately opposite the coil 10 than in the lower portion of the jacket 8, whereby the warmer fluid rises within the jacket, and the less warm fluid may be drawn off for use through the outlet plug 6. The fluid below the level of the coil 10 also is warmed by conduction through the plug 13. The warmer fluid rising within the jacket 8 replaces the cooler fluid within the upper portion of the jacket. When all the fluid within the jacket 8 becomes warm, the fluid overflows the upper end of the jacket and mixes with the cooler fluid in the upper end of the casing 1 whereby the fluid in the upper end in the casing is brought to the same temperature as that within the jacket.

In the event that the heating element 9 becomes damaged, the same may be readily removed simply by unscrewing the cap 15 from the top 3 of the casing. The damaged heating element may then be removed from the cap after which the cap may be secured to a new heating element and returned to its position with respect to the top 3. It will be readily seen that the replacing of the heating unit is but the work of a moment and may be readily accomplished without interrupting the discharge of warm fluid through the outlet plug 6.

It is thought that the many advantages of a fluid warmer in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

What I claim is:—

1. A fluid warmer comprising, a casing having an outlet plug at the bottom thereof and an inlet plug in spaced relation to the bottom thereof, a jacket secured to the bottom of the casing and extending longitudinally thereof in concentric relation thereto and

to the outlet plug, said jacket having an open upper end in spaced relation to the top of the casing, a heating element extending into the jacket, and means for detachably securing the heating element to the top of the casing, said heating element including a resistance coil of materially less length than the jacket and in alignment with said inlet plug transversely of the casing to initially warm the fluid entering the casing, said resistance coil disposed in the lower portion of the jacket but spaced from the lower end thereof to maintain the hotter fluid out of contact with the outlet plug, said heating element further including a container within which the resistance coil is hermetically sealed, said container having a heat conducting block descending therefrom into proximity to the outlet plug to warm the fluid adjacent the latter.

2. A fluid warmer comprising, a casing having an outlet at the bottom thereof and an inlet in spaced relation to the bottom thereof, a jacket extending longitudinally of the casing in concentric relation thereto and to the outlet, means closing the bottom of the jacket to the casing, said jacket having its top open to the casing, a heating element extending into the jacket and including a resistance coil of materially less length than the jacket and in alignment with said inlet transversely of the casing to initially warm the fluid entering the casing, said resistance coil disposed in the lower portion of the jacket but spaced from the lower end thereof to maintain the hotter fluid out of contact with the outlet, and a heat conductor block disposed below the resistance coil to warm the fluid adjacent the outlet.

In testimony whereof, I affix my signature hereto.

WEBSTER I. CARPENTER.
